UNITED STATES PATENT OFFICE.

OTTO F. JAEGER, OF FOND DU LAC, WISCONSIN.

STAMP-HOLDER.

No. 896,115.

Specification of Letters Patent.

Patented Aug. 18, 1908.

Application filed August 13, 1907. Serial No. 388,420.

To all whom it may concern:

Be it known that I, OTTO F. JAEGER, a citizen of the United States, residing at Fond du Lac, in the county of Fond du Lac, State 5 of Wisconsin, have invented certain new and useful Improvements in Stamp-Holders; and I do hereby declare the following to be a full, clear, and exact description of the invention, such as will enable others skilled in 10 the art to which it appertains to make and use the same.

This invention relates to new and useful improvements in stamp holders, and it has particular reference to a device of this type 15 embodying the characteristics of a paper weight, and a pin tray and including a stamp magazine and a moistening receptacle.

The invention aims as a primary object to provide a novel construction, combination 20 and arrangement of parts, the details of which will appear in the course of the following description, in which reference is had to the accompanying drawings, forming a part of this specification, like characters of 25 reference designating similar parts throughout the several views, wherein:

Figure 1 is a plan view of a stamp holder constructed in accordance with the present invention. Fig. 2 is a side elevation thereof. 30 Fig. 3 is a central longitudinal section thereof. Fig. 4 is a front elevation thereof. Fig. 5 is a transverse section on the line 5—5 of Fig. 2. Fig. 6 is a detailed plan view of a displaceable wall. Fig. 7 is a side elevation 35 of a modified embodiment of the invention, parts being shown in section.

The stamp holder embodied in the present invention comprises a cylindrical portion 1 having a wall 2 at one side thereof, which is 40 constructed with a forwardly projecting shelf 3, the latter being formed with an overhanging flange 4 extending to the front edges thereof and affording a recess 5. The portion 1 is constructed at each side thereof 45 with trays 6 for pins and other articles. Projecting horizontally from the portion 1, are spring catches 7, which are formed for engagement through openings 8, provided in a displaceable wall 9, the latter being illus- 50 trated more particularly in Fig. 6. The wall 9 includes a disk shaped portion 10, constructed with an annular groove 11, and with the forwardly projecting extension 12, which affords one of the sides of the shelf 3. 55 The disk shaped portion 10 is likewise constructed with a central opening 13, which is

adapted to surround the end of a horizontal pindle 14, carried by the side wall 2 of the portion 1. Loosely mounted upon the pindle 14 is a sleeve 15, which affords a reel for 60 a roll of stamps, which are fed through a transverse opening 16, provided in the portion 1 adjacent the shelf 3. The said shelf 3 forms the top wall of a receptacle 17, located forwardly of the portion 1 and constructed with an opening 18, the sides 19 of which are inclined forwardly and downwardly. The receptacle 17 is designed to hold water and a moistening sponge 20 which projects through the opening 18. 70

In use, the stamps are fed manually from the reel 15, and are successively detached after being passed over the sponge 20. In this action, the walls 19 serve to guide the stamps downwardly and the front wall of 75 the shelf 3, presents its edge to the line of perforations between the stamps as a cutter.

In the modified embodiment of the invention illustrated in Fig. 7, the body portion designated by the numeral 1' is of rectangular cross section and is designed as a magazine for detached stamps. With this object in view, a follower 21 is disposed within said body portion and is normally pressed upwardly by a spring 22. The body portion 1' 80 is constructed with an overhanging top wall 23, which is spaced away from the front edge of said body portion, as at 24, whereby the stamps may be successively withdrawn as they are fed by the follower 21. In this embodiment of the invention, the shelf 3 is 85 omitted, but the water receptacle constructed as previously described is retained.

A stamp holder constructed in accordance with the present invention, is simple, inexpensive to manufacture and practical and efficient in use. 95

From the foregoing description it will be seen that simple and efficient means are provided for accomplishing the objects of the invention, but while the elements herein shown and described are well adapted to serve the functions set forth, it is obvious that various minor changes may be made in the proportions, shape and arrangement of 100 the several parts, without departing from the spirit and scope of the invention as defined in the appended claims. 105

What is claimed is:

1. A stamp holder comprising a body portion having the base and side walls of the body continued to form a receptacle, a per- 110

- forated inclined wall for the receptacle, an absorbent projecting through the perforation in the wall, and a stamp holding means within the body and having a discharge opening above the perforated inclined wall.
2. A stamp holder comprising a body forming front and rear independent chambers, the front chamber having an inclined perforated wall terminating at one extremity in a top forming a shelf and at the opposite extremity in a straight vertical front wall, the rear chamber having a discharge passage above the shelf, and an absorbent means projecting through the perforation in the inclined wall.
- 5 10 15

3. A stamp holder comprising a body forming separated front and rear chambers, the front chamber having an inclined perforated face, the rear chamber having a delivery opening above the inclined perforated face, a stamp feeding means within the rear chamber, and an absorbent material projecting through the perforation in the inclined face.

20 In testimony whereof, I affix my signature, in presence of two witnesses.

OTTO F. JAEGER.
